[57] CLAIM

The ornamental design for a baby bottle holder, as shown and described.

DESCRIPTION

FIG. 1 is a perspective view of a baby bottle holder, showing my new design, the broken line showing being for illustrative purposes only and forming no part of the claimed design;

FIG. 2 is a front elevational view thereof;

FIG. 3 is a rear elevational view thereof;

FIG. 4 is a right side elevational view of the baby bottle holder, the left side view being a mirror image of the right side view;

FIG. 5 is a top plan view of the baby bottle holder; and,

FIG. 6 is a bottom plan view thereof.
